W. F. BRANEN.
AUXILIARY INTAKE FOR INTERNAL COMBUSTION ENGINES.
APPLICATION FILED MAR. 5, 1918.

1,323,006.

Patented Nov. 25, 1919.

By *Frank Lacy*, Attorney

UNITED STATES PATENT OFFICE.

WILLIAM FRANKLIN BRANEN, OF SALT LAKE CITY, UTAH.

AUXILIARY INTAKE FOR INTERNAL-COMBUSTION ENGINES.

1,323,006.

Specification of Letters Patent. Patented Nov. 25, 1919.

Application filed March 5, 1918. Serial No. 220,561.

To all whom it may concern:

Be it known that I, WILLIAM F. BRANEN, a citizen of the United States, residing at Salt Lake City, in the county of Salt Lake 5 and State of Utah, have invented certain new and useful Improvements in Auxiliary Intakes for Internal-Combustion Engines, of which the following is a specification.

This invention relates to an improved 10 auxiliary intake for internal combustion engines and has as its primary object to provide a device of this character which may be manually controlled for admitting fresh air to the intake manifold of the engine to become mingled with the fuel mixture for increasing the efficiency of such mixture as well as effecting a material saving in the quantity of liquid fuel used, a saving in the consumption of lubricating oil by the 15 engine and a lessening of the heating of the engine.

The invention has as a further object to provide a device wherein heated gases will be drawn from the exhaust manifold of the 20 engine in such manner that when the device is manually operated to admit fresh air to the intake manifold, such fresh air will be previously mixed with the said gases and heated thereby to consequently prevent cooling 25 of the fuel mixture in the intake manifold by the inrushing fresh air.

The invention has as a still further object to provide an arrangement wherein the lubricant laden vapors in the engine crank 30 case will also be drawn therefrom and directed into the intake manifold to be thence carried into the engine cylinders for lubricating the pistons and piston rings.

And a still further object of the invention 35 is to provide a device of the above described character wherein the flow of mixed exhaust gases and lubricant laden vapors from the crank case into the intake manifold will be constant so long as the engine is running 40 without regard to the manual control of the device for also at the same time admitting fresh air to the said manifold.

Other and incidental objects will appear 45 as the description proceeds, and in the drawings wherein I have illustrated the preferred embodiment of the invention, and wherein similar reference characters designate corresponding parts throughout the several views:

50 Figure 1 is a fragmentary side elevation showing my improved device applied to a

conventional type of motor vehicle engine, a portion of the vehicle body being shown in section to illustrate the disposition of the control rod of the device, and

60

Fig. 2 is a fragmentary perspective view showing the device in detail, portions of the engine being also shown to illustrate the connection between the device and the breather pipe and exhaust manifold of the engine.

65

In order that the construction, mounting and operation of my improved device may be accurately understood, I have, in the drawings, shown the said device in connection with a conventional type of motor vehicle engine 10. This engine is provided with the usual intake and exhaust manifolds 11 and 12 respectively, as well as a breather pipe 13. A portion of the vehicle body is shown at 14 and this body is provided with 70 a dash 15.

75

In carrying out the invention my improved device is formed with a body 16 providing a mixing chamber. This body is formed with a main elongated tubular portion open at its ends and provided upon its upper side with an upstanding inlet 17. Extending from the rear side of the body is a laterally directed outlet or nipple 18 which is tapped into the intake manifold 11 to support the said connection, in the manner shown in Fig. 1, at the outer side of the manifold. Threaded into the inlet 17 of the body is a pet cock 19 equipped with a valve 20 providing a fresh air inlet valve. This valve at one end is formed with a thumb piece 21 through which is fitted the laterally directed terminal of a control rod 22 for the valve. The rod 22 is, as shown in Fig. 1, inclined upwardly from the valve 20 and at its outer extremity is rotatably fitted through the dash 15 and provided with a suitable handle 23. As will be readily understood this handle may be easily operated for rotating the rod to either open or close the valve. Extending from one end of the main tubular portion of the body 16 is a preferably flexible metal pipe 24 secured at its adjacent end to the body by a coupling nut 25. The opposite end of this pipe is 80 carried to the exhaust manifold 12 and is arranged to coöperate with a nipple 25' tapped into the said manifold and receiving a coupling nut 26 connecting the said pipe with the nipple. Extending from the opposite end of the main tubular portion of the body 16 is a preferably flexible metal pipe

27 secured at its adjacent end to the said body by a coupling nut 28. The opposite end of this pipe is carried to the breather pipe 13 and is arranged to coöperate with a 5 nipple 29 tapped into the breather pipe and receiving a coupling nut 30 connecting the pipe 27 with the nipple.

As will now be seen, the pipe 24 establishes constant communication between the exhaust 10 manifold and the intake manifold through the body 16. In like manner the pipe 27 establishes constant communication between the breather pipe 13 and the intake manifold through the said body. Consequently, 15 as long as the engine is running suction in the intake manifold will act to draw in a steady flow of exhaust gases from the exhaust manifold and a steady flow of lubricant laden vapors from the engine crank case, it being understood, of course, that the breather pipe 13 with which the pipe 27 is connected, is in direct communication with the crank case. The exhaust gases and vapors so drawn in will meet within the 20 body 16 to become mingled or mixed in the mixing chamber thereof so that the vapors from the crank case will be heated by the said gases before being introduced into the manifold. Consequently, the mixture of 25 exhaust gases and vapors will not act to chill the fuel mixture from the engine carbureter. From the intake manifold, the mixture of exhaust gases and lubricant laden vapors will, of course, be delivered into the 30 engine cylinders to effect the lubrication of the pistons and piston rings. The proper lubrication of these parts will thus always be insured and the efficiency of the engine accordingly increased due to the reduction of 35 possible friction. In this connection it is to be observed that the flow of mixed exhaust gases and lubricant laden vapors into the intake manifold will be uninterrupted as long as the engine is running and without 40 regard to the manual manipulation of the air inlet valve 20.

In view of the preceding description, it will now be seen that the air inlet valve 20 may, by proper actuation of the control rod 45 22 therefor, be readily opened to admit a supply of fresh air into the body 16 to become mixed in the mixing chamber thereof with the flow of exhaust gases and lubricant laden vapors through the said body. The 50 said exhaust gases will thus also act to heat such supply of fresh air before it is introduced into the intake manifold of the engine. Chilling of the fuel mixture within the said manifold by the fresh air supply will thus 55 be obviated. Such fresh air upon becoming mingled, in the intake manifold, with the 60

fuel mixture, will act to materially enhance the efficiency of such mixture and consequently increase the efficiency of the engine accordingly. At the same time, the consumption of liquid fuel will be materially reduced. The volume of the fresh air flow may, of course, be regulated by adjustment of the valve 20.

It will, therefore, be seen that I have provided a very simple and efficient construction for the purpose set forth and a device wherein either a mixture of exhaust gases and lubricant laden vapors may be introduced into the intake manifold of the engine, 70 or a mixture of fresh air, exhaust gases and lubricant laden vapors may be delivered to the said manifold. Consequently, even though it is not desired to admit fresh air to the manifold, as, for instance, when starting the engine, or during extremely cold weather, efficient lubrication of the engine pistons may, nevertheless, be had by the introduction of the mixture of exhaust gases and lubricant laden vapors into the intake 75 manifold when the fresh air inlet valve is closed.

Having thus described the invention, what is claimed as new is:

1. In a device of the character described, 90 in combination, an internal combustion engine, a hollow body connected to the intake manifold of the engine intermediate of the ends of said manifold, a pipe extending from the body and communicating with the engine 95 crank case, and a second pipe extending from the body and communicating with the exhaust manifold of the engine.

2. In a device of the character described, 100 in combination, an internal combustion engine, a hollow body connected to the intake manifold of the engine intermediate the ends of said manifold, a pipe extending from the body and communicating with the engine crank case, a second pipe extending from 105 the body and communicating with the exhaust manifold of the engine, and a valve controlled fresh air inlet carried by the body.

3. A device of the character described including a tubular body provided with lateral inlet and outlet nipples, a fresh air valve carried by the inlet nipple, the outlet nipple being adapted to engage through an engine intake manifold for connecting the body 110 thereto, a lubricant laden vapor supply pipe connected to one end of the body, and an exhaust gas supply pipe connected to the opposite end of the body.

In testimony whereof I affix my signature. 120

WILLIAM FRANKLIN BRANEN. [L. S.]
